SLUG FINISHING MEANS FOR LINE
CASTING MACHINES

Le Roy W. Willis, Stamford, Conn., assignor to
Intertype Corporation, Brooklyn, N. Y., a corporation of New York

Application March 3, 1932, Serial No. 596,609,
and in Germany April 28, 1931

6 Claims. (Cl. 199—54)

The present invention relates to improvements in line casting machines and more especially to those employing a mold to which a line of character bearing matrices is presented and in which 5 a type slug is cast against the character bearing edges of the matrices so that the slug will bear type characters along an edge thereof, and the object of the invention is to provide means on such a machine to dress or finish the printing or 10 impression surfaces of the type characters on slugs cast therein, while the slugs are positively held in the mold and prior to their ejection therefrom.

In using line casting machines of the class 15 referred to, it has been found that the printing or impression surfaces of the type characters on slugs cast in such machines are not sufficiently smooth or even to produce good print, due to imperfections in the surfaces of the type characters, this being especially true of the larger 20 characters used for advertising, display lines or headings, and being also true of the smaller as well as the larger characters when printing is to be done directly from the slugs, these imperfections being due to several causes, as, for example, 25 the presence of air in the mold and the throat of the metal pot and which becomes mixed with the molten metal when the latter is suddenly injected into the mold and against the line of matrices, the characters on which act as pockets into 30 which such air becomes trapped, and such imperfections being also due to the fact that the type metal injected into the mold chills very rapidly and shrinkage to varying degrees takes 35 place throughout the extent of the slug.

The present invention provides means to insure an even type high finish to all of the characters on the slugs cast in the machine, thereby not only eliminating imperfections in the printed 40 or other impressions made therefrom but also conditioning the surfaces of the type characters to receive and hold ink thereon in an evenly distributed manner, thus reducing to a minimum, and in some cases eliminating entirely, the 45 necessity of dressing off the characters in the printing forms, thereby saving much time and labor and improving the printing quality of the slugs produced on these machines over that heretofore possible without requiring additional 50 manual or machine surfacing of the slugs to obtain a satisfactory ink surface and finish for the type characters thereon.

In the accompanying drawings:

Fig. 1 is a front elevation of a portion of a 55 line casting machine provided with slug dressing

or finishing means embodying the present invention;

Fig. 2 is a side elevation of the structure shown in Fig. 1 as viewed from the left thereof; and

Fig. 3 is a detailed enlarged sectional view 60 taken on the line 3—3 in Fig. 1.

Similar parts are designated by the same reference characters in the different figures.

The present invention is shown in the present instance applied to a line casting machine of 65 well known construction, 1 representing the usual rotatable mold wheel which is supported centrally for rotation and which carries a suitable number of molds 2 in which the type slugs are cast, these molds being of the usual or any 70 suitable construction and any one of the molds in use may be brought into active position, through the usual driving pinion 3, to receive metal from the usual metal pot 4 which tilts forwardly and rearwardly about its bearing 75 to carry its mouth 6 into and out of engagement with the rear face of the mold in use on the mold wheel. The mold gear support 8 constitutes a part of the machine frame as usual, and it is rigidly secured to the base 9 of the 80 machine through the connecting support or bracket 10. The mold wheel and its operating means just described may be constructed and operative in the usual and well known manner, the driving pinion 3 being adapted for manual 85 manipulation by the usual mold turning handle 7 so that any desired mold on the mold wheel may be brought into active position, such mold being in horizontal or uppermost position during the casting of a slug therein by the injection of metal into the rear side of this mold while its front face engages and is closed by a line of character-bearing matrices which are presented in the usual manner to the front of the mold, and after a slug has been cast in the 95 mold, the driving pinion 3 is rotated through the usual means to rotate the mold wheel, in the direction of the arrow, Fig. 1, through three-fourths of a revolution, thus bringing the mold containing the slug into the vertical position 100 occupied by the mold 2^a, the mold containing the slug being then positioned in front of the usual ejector which then operates to remove the slug from the mold, after which the driving pinion 3 again rotates to turn the mold wheel in the 105 same direction through the remaining one-fourth of a revolution, thereby returning the mold in use to casting position, preparatory to the casting of another slug therein.

The means shown in the present instance for 110

carrying out the present invention comprises a shelf or bracket 11 which is suitably secured to the machine frame to provide a mounting for an electric motor or other suitable driving device 12 for rotating a finishing head 13 which 5 constitutes the slug finishing element according to the present invention. This finishing head, which may be of any suitable form and consists of an abrading head of abrasive material which may have a burnishing or polishing action, is carried on a shaft 14 journalled in a bearing or sleeve 15, the latter being carried at the upper end of an arm 16 which is mounted to swing on a shaft 17, the latter being conveniently secured in a portion of the main frame, as 10 for example, an extension of the support or bracket 10 for the mold gear arm 8. A pulley 18 is fixed on the shaft 14 and is connected by a belt 19 to a cooperating pulley on the shaft of the motor or driving device 12.

15 The finishing head 13 is thus mounted so that it is at the front of the mold wheel and opposite to the path of the cavity in the mold as the latter is carried around by the rotation of the mold wheel. Means is provided for holding the finishing head in its operating position, such means comprising preferably a spring 20 one end of which is connected to a pin 21 on the machine frame and the other end of which is connected to a pin 22 on the arm 16, the tension 20 of this spring serving to swing the arm 16 and the finishing head 13 toward the mold wheel, about the shaft 17 as a center, so that the finishing head will be in a position to act on the surfaces of the type characters s on a slug S which 25 has been cast in the mold, the type characters projecting as usual forwardly beyond the front face of the mold, due to the casting of the type characters against the character faces of the matrices in which the characters are punched in intaglio, and the length of the type face on the slug being traversed by the finishing head during the rotation of the mold wheel which carries the slug containing mold past the finishing head, the finishing head being of sufficient axial 30 length to allow for the different circles in which the center and ends of the slug travel.

35 Means is provided for accurately positioning the finishing head with respect to the surfaces of the characters on the slug in the mold so that the surfaces of the type characters will be finished evenly and to uniform depth, such means preferably comprising, as shown in the present instance, an arm 24 which may be rotatably mounted on the shaft 14, this arm carrying a roller 25 which bears or travels on the forward finished face of the rim 26 of the mold wheel. The arm 24 may be set or adjusted in different angular positions about the shaft 14 by an adjusting screw 27 which is threaded in a lug 28 attached to or formed as a part of the bearing sleeve 15, such setting of the arm 24 in different angular positions about the axis of the shaft 14 while the roller 25 rests against the rim 26 of the mold wheel determining the distance of the operative face of the finishing head in front of the mold and hence its operative relation with the forward surfaces of the type characters on the slug which project forwardly from the mold.

40 Means is provided for throwing the finishing head out of operative position when desired as, for example, when the slugs are to be cast with relatively small characters which, in practice, 45 will not always require finishing, such means, as

shown in the present instance, comprising a handle 29 which may be pivoted to the machine frame as by a screw 30, the handle having a recess 31 in its under side and a cam-like surface 31^a at the rear side thereof to engage the bearing sleeve 15, so that when the handle 29 is pressed downwardly, the surface 31^a will bear against the rear side of the bearing sleeve 15 and will force the latter and the finishing head 13 forwardly or into inoperative position beyond the range of the slugs as they are carried around by the rotation of the mold wheel. When the handle 29 is lifted into the position shown in Fig. 2 the bearing sleeve 15 and the finishing head 13 will move rearwardly under the pull of the spring 20, and the finishing head will be then held in its operative position to act upon the type surfaces of the slugs carried around by the mold wheel, the rearward movement of the finishing head being limited by engagement of the set screw 27 with the arm 24 and the contact of the roller 25 on the latter with the rim 26 of the mold wheel, the contact of the roller 25 with the rim of the mold wheel gauging the depth of the dressing or finishing action produced by the finishing head upon the type faces of the slugs. The finishing head 13 may be removably but securely held on the shaft 14 by providing the latter with a flat or squared portion and providing the finishing head with a set screw 32.

50 In order that the mold disk may be thrown forwardly out of its normal operating position, after the usual vise in the machine has been dropped, and thus provide access to the mouth-piece of the metal pot, as is occasionally done in machines of this class, without interference from the slug finishing device, one end of the spring 20, as for example the rear end as shown, is provided with an open hook to detachably engage the pin 21, detachment of the spring from this pin enabling the arm 16 and the finishing head and other parts carried thereby to swing forwardly about the shaft 17 until the arm 16 rests against a lug 11^a which may be formed as a part of the bracket 11, the finishing head being thus permitted to assume a position beyond the front of the mold wheel so that it will not interfere with forward withdrawal thereof when such is desired.

55 The operation of a line casting machine equipped with slug finishing means as hereinbefore described is as follows: Assuming that the uppermost mold 2 is in use and is in operative casting position, a type slug would be cast therein in the usual manner, after the metal pot 4 has been moved forwardly to lock tightly against the rear face of the mold, and after the metal pot has receded rearwardly following the cast, the mold wheel will be caused to rotate in the usual manner through three-fourths of a revolution in the direction indicated by the arrow in Fig. 1, thus bringing the mold containing the slug to the vertical position represented by the position occupied by the mold 2^a, and during this rotation of the mold wheel, the mold containing the slug will pass the finishing head 13 and during such passage of the mold containing the slug the front surfaces of the character bearing edge of the slug will be finished by the dressing or finishing head 13 which is revolved by the motor or driving means 12, preferably in the direction of the arrow in Fig. 2, the electric motor or driving means 12 for the finishing head preferably running continuously while the line casting machine is in operation. The dressing

60 65 70 75 80 85 90 95 100 105 110 115 120 125 130 135 140 145 150

or finishing action thus produced by the head 13 upon the character bearing edge of the slug while the latter is being carried from casting position to ejecting position by the rotation of 5 the mold wheel causes the characters on the slug to be finished or dressed to exactly standard type high measure, and such finishing operation moreover is performed quickly and thoroughly while the slug is still held firmly and 10 positively in the mold.

The adjusting member 24 permits accurate setting of the finishing head 13 to regulate its depth of action with respect to the type characters on the slugs, and the contact of the 15 roller 25 on this adjusting member with the face of the mold wheel rim 26 guides the finishing head so that it will always remain a true distance from the faces of the molds on the mold wheel, notwithstanding that the mold wheel 20 might run slightly out of true, due to warpage or looseness in its bearings.

I claim as my invention:

1. In a line casting machine, the combination of a mold carrying member, and a cooperative 25 rotary abrading device to act upon the type face of a slug in a mold carried by said member, said member and device being relatively movable to cause the finishing device to traverse the length of the type face of the slug and finish evenly 30 the cast surfaces of said type face.

2. In a line casting machine, the combination of a rotatable mold wheel carrying a type slug casting mold, and a rotary power driven abrading and polishing device located opposite to the face 35 of the mold wheel to act on the type face of a slug in the mold during rotation of the mold wheel to evenly finish and polish the cast surfaces of said type face.

3. In a line casting machine, the combination of a rotatable mold wheel carrying a type slug casting mold, a dressing device located opposite to the face of the mold wheel to act on the type face of a slug in the mold during rotation of the mold wheel, means yieldingly acting to move said device into operative position, and means for rendering said device inoperative.

4. In a line casting machine, the combination of a rotatable mold wheel carrying a type slug casting mold, a dressing device mounted relatively to the mold wheel to act on the type face of a slug in the mold during rotation of the mold wheel, gauging means between the mold wheel and said device for positioning said device relatively to the type face of the slug, means for yieldingly holding said device in operative position against said gauging means, and means for rendering said device inoperative.

5. In a line casting machine, the combination of a member carrying a type slug casting mold, a cooperative finishing device to act upon the type face of a slug in the mold, said member and device being relatively movable to cause the finishing device to traverse the length of the type 100 face of the slug, and gauging means interposed between said member and device for relatively positioning the latter and the type face of the slug.

6. In a line casting machine, the combination of a rotatable mold wheel carrying a type slug casting mold, a dressing device mounted to act on the type face of a slug in the mold during rotation of the mold wheel, and a gauging device for the dressing device connected to the latter 110 and bearing on and guided by the mold wheel.
